UNITED STATES PATENT OFFICE.

CYRUS C. EARNIST, OF RICEVILLE, IOWA.

ATTACHMENT FOR ADDING-MACHINES.

No. 824,416.

Specification of Letters Patent.

Patented June 26, 1906.

Application filed August 1, 1905. Serial No. 272,228.

To all whom it may concern:

Be it known that I, CYRUS C. EARNIST, a citizen of the United States, residing at Riceville, in the county of Mitchell and State of Iowa, have invented certain new and useful Improvements in Attachments for Adding-Machines; and I do hereby declare the following to be a full, clear, and exact description of the invention, such as will enable others skilled in the art to which it appertains to make and use the same.

My invention relates to apparatus of that class used for mechanically assisting arithmetical calculations, and it is more particularly an attachment for mechanisms generally known as "adding-machines."

An object of the invention, which is particularly adapted for use upon the "Burroughs" adding-machine, is based upon the well-known fact that such a machine after accumulating 10,000,000.00, or whatever may be its capacity, drops the amount and accumulates anew, beginning with .01.

Another object of the invention is to provide means whereby by the process of addition any problem in subtraction can be solved mechanically through the use of the ordinary adding mechanism.

A still further object is to provide an attachment of this character which can be readily attached to adding-machines without in anywise changing the mechanism thereof and which does not interfere with the use of the machines for adding purposes.

With these and other objects in view the invention consists of series of keys adapted to respectively actuate the keys of the machine to which the attachment is applied and which are provided with selective means whereby the mechanism of the complement of any depressed key may be operated so that by a fixed rule of addition the mechanism of the adding-machine will be caused to mechanically register the result in any problem of subtraction.

The invention also consists of certain other features of construction and combination of parts, which will be hereinafter more fully described, and pointed out in the claims.

In the accompanying drawings I have shown the preferred form of my invention.

In said drawings, Figure 1 is a perspective view of an adding-machine of the Burroughs type having my improved attachment thereon. Fig. 2 is a plan view of the

mechanism of the attachment, the casing being removed and the plungers of the keys of the attachment, as well as a portion of one of the selective bars, being shown in section. Fig. 3 is a vertical section through the attachment on line 3-3, Fig. 2, and showing one of the keys of the attachment in position upon a key of the machine. Fig. 4 is a section on line 4-4, Fig. 2. Fig. 5 is a side elevation of one of the selective bars. Fig. 6 is an elevation of one of the keys of the attachment and its plunger, said plunger being partly broken away; and Fig. 7 is an enlarged perspective view of the mechanism for stopping the actuation of the paper-carrier and printing mechanism during certain operations of the attachment.

By the term "complement," which I use throughout the description and claims of this application, I desire to designate the number which when added to another number in the same column makes a total equal to the largest number appearing in said column. In other words, the complement of a depressed key is another key in the same column the number of which when added to the number of the depressed key equals nine.

Referring to the figures by numerals of reference, 8 is a casing of any suitable form and preferably of such a size as to fit upon the top of an adding-machine and to completely inclose the keys projecting therefrom. In the drawings I have shown my invention applied to a Burroughs adding-machine, the mechanism of which is well known to persons familiar with the art and which therefore need not be described by me. This casing has a bottom 9 located at a sufficient distance from the lower edges of the side walls of the casing to permit the keys 10 of the adding-machine 11 to normally rest close to it. Parallel series of plungers 12 are mounted within apertures 13, formed within the top and bottom of the casing 8, and are so disposed within said casing that when the same is in position upon the adding-machine one plunger will rest upon and be supported by each key 10 of the machine. These plungers are prevented from becoming displaced by securing the casing 8 rigidly to the top of the machine 11. Any desired means may be employed for fastening the attachment to the machine; but I preferably utilize angular brackets 14, which overlap the top of the machine 11 and are clamped thereon by set-screws 15.

Extending upward from the bottom 9 of casing 8 are guide-posts 16, which extend through the corners of a rectangular frame or carriage 17, located within the casing 8. 5 This carriage has supporting-pins 18 extending inwardly from its sides and slidably mounted within slots 19, formed within supporting-links 20. These links are arranged in pairs, one pair being located adjacent each 10 side of the frame, and the members of each pair are pivoted together and normally disposed at an angle to each other. The lower ends of the links 20 are slidably connected to guides 21, secured to the bottom 9, adjacent the front and rear of the casing, and the pivots 22 of the links 20 are slidably mounted in slots 23, formed in arms 24, which extend upward from the centers of the sides of frame 17. One of the links 20 has an arm 25 extending 15 forward from it, and on this arm are located two extensions 26 and 27, which project through apertures in the top of casing 9 and have keys 28 and 29, respectively. A hanger 30 extends downward from the arm 25 and 20 is normally supported by a spring 31, which is interposed between said hanger and the bottom 9. The guides 21, hereinbefore referred to, have cross-rods 32 slidably mounted within them, and these rods rigidly connect the links 20 at opposite sides of the 25 frame 17. It will be understood that spring 31 exerts a constant upward pressure upon hanger 30 and arm 25 and tends, therefore, to hold the keys 28 and 29 normally in their 30 uppermost positions. Said spring also holds the pivots 22 and the two sets of links 20 normally in the upper ends of the slots 23, and as the links 20 are engaged by pins 18, extending from the sides of frame 17, it is 35 obvious that the one spring 31 also serves to hold the frame 17 normally in a raised position.

The two keys 28 and 29 are located in a column, preferably at the left of the series of 40 plungers 12, and also located in a column therewith is a key 33, which is connected to one end of an angular lever 34, mounted within the casing 8 and pivoted at its rear end to the top of said casing, as shown at 35. 45 The heel 36, formed by this lever, is adapted to bear against a cross-lever 37, which is pivoted at one end to one side of casing 8, as shown at 38, while its other end is slotted, as at 39, and is engaged by a pin 40, depending 50 from a bar 41, constituting one member of a "resetting" device. This bar 41 is slidably mounted within the front and back portions of frame 17 and is preferably located adjacent the center of said frame. A head 55 42 in the form of a cross-bar extends in front of and parallel with the front of frame 17 and is for the purpose hereinafter described. When the bar 41 is in its rearward or "set" 60 position, the same is held against movement by a locking-bar 43, which fits within a notch

44 in bar 41 and extends throughout the width of frame 17. Locking-bar 43 has parallel arms 45 at its ends, which are pivoted to brackets 46, extending from frame 17, and a lever 47, fulcrumed upon the bottom 9 of 70 casing 8, preferably adjacent the right side of the frame 17, extends under the locking-bar 43. This lever 47 has a key 48, which is disposed above the casing 8 and is adapted when depressed to cause the lever 47 to lift 75 the locking-bar 43 out of the notch 44. The bar 41 has its rear end reduced in thickness to form a beveled shoulder 49, whereby after the locking-bar 43 has been raised out of the notch 44 and the bar 41 has moved forward 80 a predetermined distance, as will be herein-after more fully described, said locking-bar will ride down the inclined shoulder 49 and reassume a position in the same horizontal plane as that assumed by it when in the 85 notch 44.

Extending between the hanger 30 and the lever 34 is a lever 50, which is fulcrumed at a point within the casing, as shown at 51, and extends through a slot 52, formed in the 90 rear wall of casing 8. This lever is contacted normally by a pin 53, extending laterally from hanger 30, and by a pin 54, which extends laterally from lever 34. The rear end of lever 50 extends downward and overlaps 95 the ratchet 55, which is ordinarily employed in connection with the platen 56 of the paper-carrier of the adding-machine. A shield 57 extends laterally from the end of lever 50 and is parallel with the platen and located 100 at a point just below where the type of the printing mechanism contacts with the paper on the platen. An arm 58 projects from the lever 50 and under a pin 59, which extends from a dog 60, which actuates ratchet 105 55. It is therefore apparent that when the rear end of lever 50 is raised by depressing any of the keys 28, 29, and 33 the arm 58 will contact with the pin 59 and raise the dog 60 out of engagement with the ratchet 55, 110 and at the same time the shield 57 will be lifted into position between the platen or the paper thereon and the type, so that no impression will be made by the type on the paper; but said impression will instead be 115 received by the shield. These parts are adapted to be locked in raised position by means of a spring-pressed plunger 61, mounted in guides 62, extending from the rear wall of casing 8. A spring 63 bears at opposite 120 ends upon one of the guides 62 and on a collar 64, secured to the plunger, and this spring serves to normally press one end of the plunger 61 against the lever 50. When, however, the rear portion of the lever is 125 raised, the spring will throw the plunger under said lever, so as to support it in raised position until the plunger shall have been retracted. In order to retract the plunger at the proper time, I provide the same with 130

an arm 65, which overlaps one side of casing 8 and movably engages a bell-crank lever 66, which is pivoted on a bracket 67, extending laterally from casing 8. One arm of this lever extends into the path of the operating-lever 68 ordinarily employed by adding-machines, and when said lever is thrown back it will bear against the bell-crank lever 66 and pull the plunger 61 toward it, so that the rear end of lever 50 may fall by gravity into position in the path of the plunger 61, as shown in Fig. 7. A fourth key 69 is located in the column with keys 28, 29, and 33. This key 69, however, is merely located on one end 15 of a plunger 12, which is adapted to rest by gravity on the "total-key" of the adding-machine.

As hereinbefore stated, series of plungers, all of which are similar to the plunger 12, are mounted within the top and bottom of casing 8, and one plunger rests by gravity on each key of the adding-machine. These keys are ordinarily disposed in parallel rows, the keys of each row being designated by numerals 1 to 9, successively. The first row at the right of the machine, when said machine is used in computing amounts in dollars and cents, indicates "hundredths," the second "tenths," the third "units," the fourth "tens," the fifth "hundreds," &c. The second plunger of the hundredths-column, which I have designated by the numeral 12^a in Fig. 2, has a pin 70 extending laterally therefrom and which is normally overlapped by an arm 71, formed at one end of a rotatable rod 72, mounted on the bottom 9 of the casing 8. Another arm 73 is located at the other end of this rod and is overlapped by a pin 74, projecting laterally from the lever 34. This pin 74, however, does not normally contact with arm 73, but only comes in contact therewith just prior to the completion of the downward movement of lever 34. A slight downward movement is therefore imparted to arm 73 just as the lever 34 completes its downward movement; but this movement of said arm 73 is sufficient to cause the depression of plunger 12^a, which will depress the ".02" key of the adding machine.

Each plunger 12 has a stop-pin 75 and an actuating-pin 76 extending from one side thereof, said pins being disposed in vertical alinement. The pins on all the plungers project in the same direction, and located between every two series of plungers is a selective bar 77, which is arranged close to the ends of pins 75 and 76 and is slidably mounted at its ends within the front and rear portions of frame 17. Each of these selective bars 60 and bar 41 are channeled and rectangular in cross-section, and located within each of the bars and bar 41 is a coiled spring 78, secured at one end to the bar and at its other end to the front of the frame 17. This has been 65 clearly shown in Fig. 2. It is therefore obvi-

ous that the springs 78 exert a continuous forward pull upon their respective bars. The front ends of these bars normally contact with the head 42 of the "reset" device. Each selective bar has two parallel sets of laterally-projecting pins which overlap the pins on the plungers 12. The pins 79 constitute the upper set on each selective bar, and the pins 80 constitute the lower set, and are so disposed in relation to each other that when the first key in any series is depressed and its selective bar released, the first pin 79 will come into contact with and be stopped by the pin 75 of the depressed key, and at the same time one of the pins 80 will arrive in position 75 directly above the pin 76 of the eighth key in the same series, said key being the complement of the first key, because the sum of the two keys equals nine, or the highest number indicated by any key in the series. Should the second or "2" key be depressed, the pin 79 nearest thereto will be stopped by the pin 75 of the depressed key, and at the same time one of the pins 80 on the shifted selective bar 80 will arrive in position above the pin 76 of the complement of the depressed key which is the seventh key from the front in the same series. This graduation of the pins 79 and 80 is continued, so that no matter what key of the series is depressed when its selective 90 bar is released one of the pins 80 on said bar will assume a position above the complement of the depressed key. In order that the selective bar may be locked in position with one of its pins 80 above the pin 76 of the complement of the depressed key, I provide 95 said selective bar with a series of locking-pins 81, equal in number to the number of plungers 12 within each column and which are adapted to coöperate with the locking-bar 43 in the manner hereinafter described. If it is desired to add any particular amounts upon the machine on which this attachment is located, the keys are depressed as ordinarily and the lever is then actuated to produce 100 the operation of the mechanism and to cause the sums to be properly recorded and totaled. If, however, it should be desirable to subtract a sum from a given amount, the following operation is carried out: If, for example, \$2 are to be subtracted from \$100, the 105 "100" key is depressed as ordinarily, and the lever 68 is then drawn forward and released, so that the "100" will be printed upon the paper on platen 56, and said paper will 110 then be shifted upward so as to be ready to receive the next sum thereunder. The operator then depresses the "\$2" key, which causes its pin 75 to assume a position in front of one of the pins 79 of its selective bar 77. 115 The key 48 is then depressed and raises the locking-bar 43 from its position in front of the locking-pins 81 on all of the bars 77. Said bar is also raised from the notch 44 in the bar 41. Simultaneously with the raising 120

of the locking-bar 43 all of the springs 78 will draw their respective bars 77 forward. All of these bars will go forward to the limits of their movement with the exception of that bar belonging to the "\$2" key which has been depressed. This bar, instead of going forward its entire distance, will only travel until one of its pins 79 comes in contact with pin 75, and when it assumes this position one of its pins 80 will arrive in position directly over a pin 76 of the complement of the "\$2" key, which is the "\$7" key. All of the other selective bars 77 will stop with one pin 80 in position over the pins 76 of their respective "\$9" keys. As soon as bar 41 of the reset device reaches its forward position the bar 43, which has been traveling thereon, moves down the beveled shoulder 49, or, in other words, shoulder 49 passes from under bar 43, which assumes its engagement with the pins 81 of all the selective bars and locks said bars in the positions assumed by them. The selective bars now having been set and locked in proper position, as just stated, lever 68 is drawn forward to print the "\$2" indicated by the key which still remains set and to release said key.

So far the adding mechanism has been operated only in the ordinary way; but the selective bars have been set and locked in position for the following operation: The key 28 is depressed, and as it is connected to the extension of one of the links 20 it will cause the rods 32, to which all of the links 35 are rigidly secured, to travel apart, and the entire carriage 17 will therefore be forced downward on its guides 16 and all of the selective bars will move downward therewith. It is therefore obvious that those keys 40 whose pins are overlapped by the pins of the selective bars will be depressed by this operation. Lever 68 is then swung forward and permitted to return. It is obvious that under ordinary conditions this operation of the lever would cause the result (9999997.99) 45 to be printed and the slip of paper in the machine to be shifted automatically. This result will not occur, however, because when key 28 is depressed the pin 53, connected to it, 50 will depress the forward end of lever 50 and will raise the dog 60 out of engagement with ratchet 55 and also lift the shield 57 into position to receive the impression of the type. The plunger 61 will also spring into position 55 under the lever and hold it with the parts 60 and 57 raised. Therefore instead of the result above mentioned being recorded on the paper slip it will be received by the shield 57 and the platen will not be rotated.

When the plunger 61 springs into engagement with lever 50, the bell-crank lever 66 60 will swing forward; but when lever 68 returns after having been drawn forward it will press the bell-crank lever 66 back to its 65 normal position and cause the plunger 61

to release lever 50, and therefore the shield 57 and the dog 60 will drop to their normal positions. The next key 29 is then depressed and lever 68 operated, and the operation above described will be, therefore, 70 exactly repeated, because key 69 is connected to the same parts as is key 28. The operator then depresses the key 33. This operation causes the actuation of lever 50 in the manner above described, because a pin 75 54, connected to the key 33, bears on lever 50. It also causes the heel 36 of the said lever 34 to press against lever 37 and pull back bar 41 of the reset device. Said bar 80 will draw the head therewith, and said head will come in contact with the forward ends of all of the selective bars and will slide them back to their initial positions. During this return movement of bar 41 and before its head touches the selective bars its beveled 85 shoulder will come in contact with the locking-bar 43 and raise it above all of the pins 81, and therefore there is nothing to prevent the return of said bars to their initial positions. As soon as said positions have been 90 assumed the locking-bar 43 will drop into the notch 44 and all of the parts will therefore be held in position for the repetition of the foregoing operations. Immediately prior to the completion of the downward movement of key 33 its pin 74 comes in contact with arm 73 of the rotatable rod 72, and as this rod is provided with an arm 71, which bears on pin 70 of the ".02" key, said ".02" key will be depressed just as the selective bars return to 95 their initial positions. As soon as the key 33 has been depressed to produce all of these results the lever 68 should be drawn forward and released, so that the ".02" will be duly recorded within the machine. Key 69 is 100 then depressed so as to actuate the "total-key" of the machine, and upon pulling the lever 68 forward and releasing it the result of the problem in subtraction will be indicated mechanically upon the strip. 105

In connection with the foregoing description of my improved attachment I will state that the Burroughs adding-machine constantly adds the amounts indicated by depressed keys until the total reaches the capacity of the machine, which in most cases is 110 10,000,000.00, and when the total passes that point the machine accumulates anew, beginning with .01. This characteristic of the machine is utilized by me for producing the desired result by the manipulations hereinafter described. It is thought that the following example will clearly present the process whereby the foregoing principle is utilized to subtract by means of addition: When 115 the amount listed in the machine is 100.00, 100.00 is accumulated by the mechanism of the adding-machine. When the 2.00 which is to be subtracted from 100.00 is 120 listed in the machine, said machine accumu- 125

lates the total of 102.00. When the complement of 2.00—to wit, 9,999,997.99—is selected by the mechanism employed by me and listed in the machine, said machine will 5 accumulate 10,000,099.99. As hereinbefore stated, however, the machine will not indicate any amount above 10,000,000.00, and when this point is reached it will list anew, beginning with .01, and the amount listed as 10 the result of this last-described operation will be 99.99. Should the operation be stopped at this point, it will be seen that the result (99.99) would not be the correct remainder of the problem in subtraction. However, this proper result is produced by 15 repeating the listing of the complement 9,999,997.99, which causes the machine to accumulate that amount plus the amount 99.99 already listed, making a total of 20 10,000,097.98, and as this amount runs beyond the capacity of the machine said machine will accumulate anew, beginning with .01, until 97.98 is listed thereby. The last 25 operation necessary to complete the problem in subtraction is to list in the machine the amount .02, and said machine then accumulates the amount 98.00, which is the remainder desired.

The operations above described can be better seen by the following tabulation:

	Amount written.	Amount accumulated.
	100.00	100.00
	2.00	102.00
35	9,999,997.99	10,000,099.99
	9,999,997.99	10,000,097.98
	.02	98.00

In the operation of the above problem indicating the amounts accumulated I have 40 indicated the ciphers in the amounts ranging above 10,000,000.00; but it will be understood that these ciphers will be eliminated automatically by the adding-machine, and only the numbers 99.99 and 97.98, respectively, will be listed. Under ordinary conditions the foregoing operation of the adding-machine would list upon the paper the following result:

50	100.00
	2.00
	9,999,997.99
	9,999,997.99
	.02
55	98.00

While the problem herein explained and carried out is a very simple one, merely showing the manner of subtracting 2.00 from 60 100.00, it will be understood that a problem involving any amounts can be solved in this manner. It will of course be understood that no unusual space will occur upon the strip of paper between the \$2 and the 65 result, (\$98,) because the platen is not ro-

tated when the keys 28, 29, and 33 are depressed, nor is any impression made upon the strip. Therefore while the problem carried out in the machine is the same as that above indicated the result, as appearing upon the 70 strip, will be as follows:

100 00	
2 00	
98 00	75

It will be seen that any problem in subtraction can be solved in this manner, it merely being necessary at any time to depress the keys in the order mentioned and pull operating-lever 68 after each key 48, 28, 29, 33, and 69 has been depressed. The proper complement of the sum to be subtracted will always be actuated in the manner described, so that the proper result will be invariably obtained. 85

It will be noticed that the entire attachment can be readily placed upon a machine; but it is obvious that I do not restrict myself to such disposition of my improved subtracting mechanism, for, if desired, the same can 90 be incorporated within the body of the machine by providing pins 75 and 76 on the plungers of the keys 10 instead of upon auxiliary keys such as shown by me.

Having thus fully described my invention, 95 what I claim as new, and desire to secure by Letters Patent, is—

1. The combination with a series of keys; of mechanism for automatically selecting in said series the complement of any of said 100 keys when actuated.
2. The combination with a series of keys; of actuating means, and mechanism for automatically selecting in said series the complement of any of said keys and placing it in operative relation with the actuating means. 105
3. The combination with a series of depressible keys; of an actuating device, and mechanism for automatically placing the complement of a depressed key in operative 110 relation with the actuating device.
4. The combination with a series of depressible keys; of an actuating device, and mechanism for automatically placing the complement of any key, when depressed, into 115 operative relation with the actuating device.
5. The combination with a series of depressible keys; of an actuating device, mechanism for automatically placing the complement of a depressed key into operative relation with the actuating device, and mechanism for returning said first-mentioned mechanism to its initial position. 120
6. The combination with series of keys; of mechanism for automatically selecting in each series the complement of any depressed key in the same series. 125
7. The combination with a series of keys; of mechanism for automatically selecting in said series the complement of any of said 130

- keys when depressed, and mechanism for returning the selective mechanism to its initial position.
8. The combination with series of keys; of separate mechanism for automatically selecting in each series the complement of any key in the same series, and mechanism for returning the selective mechanisms to their initial positions.
10. 9. The combination with series of keys; of mechanism for automatically selecting in each series the complement of any of said keys, and a lock for holding said selective mechanism upon the completion of its selection.
15. 10. The combination with a series of keys; of mechanism for automatically selecting in said series the complement of any of said keys, a lock for holding said mechanism upon the completion of its selection; and mechanism for releasing the selective mechanism and returning it to its initial position.
20. 11. The combination with a series of keys; of a selective device for said series, means upon the keys for limiting the movement of the selective device, and means upon the selective device for automatically registering with the complement of the key limiting the movement of the device.
25. 12. The combination with a series of keys; of a slide for said series, means upon each key for independently limiting the movement of the slide, and means upon the slide for automatically selecting the complement of the key limiting the movement of said device.
30. 13. The combination with a series of keys; of a spring-controlled selective device, means operated by the depression of any key for limiting the movement of the selective device, and means upon said selective device for automatically registering with the complement of the depressed key.
35. 14. The combination with a series of keys; of a spring-controlled slide, means adapted, when a key is depressed, to limit the movement of the slide in one direction, and means upon said slide for automatically selecting the complement of the depressed key.
40. 15. The combination with a series of keys; of a spring-controlled slide, means for limiting the movement of said slide when any one of the keys is depressed, means upon the slide for automatically selecting the complement of the depressed key, and an actuating device for depressing the slide and the selected complement.
45. 16. The combination with series of keys; of a spring-controlled selective device for each series, means operated by the depression of any key for limiting the movement of its selective device in one direction, means upon each selective device for automatically selecting the complement in the same series with a depressed key, and means for simultaneously returning the selective devices to their initial positions.
50. 17. The combination with series of keys; of a spring-controlled selective device for each series, means operated by the depression of any key for limiting the movement of its selective device in one direction, means upon each selective device for automatically selecting the complement in the same series with a depressed key, means for simultaneously returning the selective devices to their initial positions, and means for automatically locking the selective devices when returned.
55. 18. The combination with series of keys; of a selective device for each series, means operated by the depression of any key for limiting the movement of its selective device, means upon each selective device for automatically registering with the complement of the depressed key, an actuating device for simultaneously depressing the selective devices and the complement engaged thereby, and means for resetting the selective devices in their initial positions.
60. 19. The combination with a series of keys; of a selective device, means operated by the depression of a key for limiting the movement of the selective device, means upon said selective device for automatically registering with the complement of the depressed key, means for depressing the selective device and the complement registering therewith, and a locking device for holding the selective device prior and subsequent to its adjustment.
65. 20. The combination with a series of keys; of a selective device, means operated by the depression of a key for limiting the movement of the selective device, means upon said selective device for automatically registering with the complement of the depressed key, means for depressing the selective device and the complement registering therewith, and a locking device for holding the selective device prior and subsequent to its adjustment, and mechanism for automatically "resetting" the selective device subsequent to its adjustment.
70. 21. The combination with a series of keys; of a selective device, means operated by the depression of a key for limiting the movement of the selective device, means upon said selective device for automatically registering with the complement of the depressed key, means for depressing the selective device and the complement registering therewith, a locking device for holding the selective device prior and subsequent to its adjustment, mechanism for automatically "resetting" the selective device subsequent to its adjustment, and means actuated by said mechanism for unlocking the selective device during the "resetting" operation.
75. 22. The combination with a series of keys;

of a selective device, means operated by the depression of a key for limiting the movement of the selective device, means upon said selective device for automatically registering with the complement of the depressed key, means for depressing the selective device and the complement registering therewith, a locking device for holding the selective device prior and subsequent to its adjustment, mechanism for automatically "resetting" the selective device subsequent to its adjustment, and manually-operated means for unlocking the selective device.

23. The combination with a series of keys; of a selective device, means operated by the depression of a key for limiting the movement of the selective device, means upon said selective device for automatically registering with the complement of the depressed key, means for depressing the selective device and the complement registering therewith, a locking device for holding the selective device prior and subsequent to its adjustment, mechanism for automatically "resetting" the selective device subsequent to its adjustment, means actuated by said mechanism for unlocking the selective device during the "resetting" operation, and manually-operated means for unlocking the selective device prior to the selective operation.

24. The combination with a series of keys; of actuating means, means for automatically selecting in said series the complement of any of said keys and coupling it with the actuating means, and mechanism operated by the actuating means adapted to prevent the actuation of the platen and the recording of the operation of an adding-machine.

25. The combination with a series of keys; of a selective device, means operated by the depression of a key for limiting the movement of the selective device, means upon the selective device for automatically registering with the complement of a depressed key, means for actuating the selective device to depress the complement alining therewith, means for manually returning the selective device to its initial position, a key actuated by said means, and mechanism operated by said means adapted to prevent the actuation of the platen and the recording of the operations of an adding-machine.

26. The combination with a depressible carriage and a key for actuating the same; of a series of keys adjacent the carriage, a selective device mounted within the carriage, means actuated by the depression of any key for limiting the movement of the selective device, and means upon the selective device for automatically registering with, and adapted to bear upon, the complement of the depressed key.

27. The combination with a resilient

supported depressible carriage and a key for actuating the same; of a series of keys adjacent the carriage, means movably mounted within the carriage for automatically selecting in said series the complement of any of said keys.

28. The combination with a resiliently-supported carriage and means for manually depressing the same; of a series of keys adjacent the carriage, means movably mounted within the carriage for automatically selecting in said series the complement of any of said keys, and manually-operated means upon the carriage for returning the selective means to its initial position.

29. The combination with a resiliently-supported carriage, guides therefor, and means for manually depressing the carriage; of series of keys adjacent the carriage, slides mounted within the carriage and adjacent the series of keys, means operated by the depression of any key for limiting the movement of the slide of its series, means upon the slide for automatically registering with the complement of the depressed key, said means being adapted to bear upon and actuate the complement when the carriage is depressed.

30. The combination with a resiliently-supported carriage, guides therefor, and means for manually depressing the carriage; of series of keys adjacent the carriage, slides mounted within the carriage and adjacent the series of keys, means operated by the depression of any key for limiting the movement of the slide of its series, means upon the slide for automatically registering with the complement of the depressed key, said means being adapted to bear upon and actuate the complement when the carriage is depressed, a "resetting" device mounted within the carriage for returning the slides to their initial position, and means upon the carriage for manually actuating the "resetting" device.

31. The combination with a resiliently-supported carriage and means for manually actuating the same; of series of keys adjacent the carriage, spring-controlled slides mounted within the carriage and adjacent the series of keys, means operated by the depression of any key for limiting the movement of the slide of said series, means upon each slide for automatically alining with the complement of the depressed key, said means adapted to depress said complement when the carriage is actuated, means upon the carriage for automatically locking the slides in adjusted position, and a manually-operated unlocking device upon the carriage.

32. The combination with a resiliently-supported carriage and means for manually actuating the same; of series of keys adjacent the carriage, spring-controlled slides mounted within the carriage and adjacent the series of keys, means operated by the de-

pression of any key for limiting the movement of the slide of said series, means upon each slide for automatically alining with the complement of the depressed key, said means 5 adapted to depress said complement when the carriage is actuated, means upon the carriage for automatically locking the slides in adjusted position, a manually-operated unlocking device upon the carriage, and means 10 upon the carriage for automatically unlocking and "resetting" the slides.

33. The combination with an adding-machine having a rotatable platen and a dog for actuating the platen; of a series of keys upon 15 said machine, a selective device for said series, means operated by the depression of a key for limiting the movement of the selective device, means upon the selective device for automatically registering with the complement of the depressed key, means for manually depressing the selective device and the complement alining therewith, a shield overlapping the platen, a dog-lifting device, mechanism actuated by said means for automatically operating the shield and dog-lifting device, a lock for holding said shield and device in the position to which they are adjusted, 20 and a lock for holding said shield and device in the position to which they are adjusted.

34. The combination with an adding-machine having a rotatable platen and a dog for actuating the platen, and an actuating-lever; 25

or a series of keys upon said machine, a selective device for said series, means operated by the depression of a key for limiting the movement of the selective device, means upon the 35 selective device for automatically registering with the complement of the depressed key, means for manually depressing the selective device and the complement alining therewith, a shield overlapping the platen, a dog-lifting device, mechanism actuated by said means for automatically operating the shield and dog-lifting device, a lock for holding said shield and device in the position to which they are adjusted, and means operated by 40 the actuating-lever for unlocking said shield and dog.

35. An attachment for adding-machine comprising a casing; keys therein adapted to be supported by and to actuate the corresponding keys of an adding-machine, means within the casing for automatically selecting the complement of any key depressed, and manually-operated means within said casing 45 for actuating the selected complement. 50

In testimony whereof I have signed my name to this specification in the presence of two subscribing witnesses.

CYRUS C. EARNIST.
